UNITED STATES PATENT OFFICE

COREY C. BRAYTON, OF BERKELEY, CALIFORNIA, ASSIGNOR TO AMERICAN MANGANESE STEEL COMPANY, OF CHICAGO, ILLINOIS, A CORPORATION OF MAINE

NIGGER BAR

Application filed August 25, 1927. Serial No. 215,299.

The invention pertains to a log turner or nigger bar, and particularly to a manganese cast steel nigger bar, the body of which is of integral construction and is provided with teeth pivoted to the bar in a novel manner.

The main problem in the use of a nigger bar for turning logs is the abuse it gets rather than the use to which it is put. If a log is turned "on the fly", the carriage is often moving when the teeth are in contact with the log, and it is to be readily understood that this is very hard on the bar, and in addition to this, a careless sawyer is apt to hook onto the carriage head block, which may be still harder on the bar, and unless the bar is of inherent rugged construction and material, many breaks occur with their consequent expensive repair bills.

It is therefore an object of this invention to provide an inexpensive nigger bar of rugged construction, which is of long life and is inexpensive to manufacture and maintain.

Another object is to provide an integral manganese cast steel nigger bar instead of the usual carbon steel one, a portion of which is of I-beam construction, and is provided with teeth pivoted to said bar in a novel manner.

A further object is to provide an integral nigger bar provided with a spacer at the top thereof joining the flanges of the tooth slot, said spacer having a rounded portion toward the log engaging side of the bar.

A more specific object is to provide a tooth pivot for a nigger bar which is of novel design for maintaining the pivot in tight disposition.

Other and more specific objects will readily appear from the detailed description and claims appended hereto.

In the drawings, wherein similar reference characters are used to designate similar parts—

Figure 1 is a side elevation partly in section of the improved nigger bar;

Figure 2 is a broken edge elevation of the improved nigger bar, a portion being in section, taken substantially on the line 2—2 of Figure 1;

Figure 3 is a plan taken substantially on line 3—3 of Figure 1;

Figure 4 is a side elevation of a portion of the head of the nigger bar, showing the disposition of the teeth;

Figure 5 is a side elevation of Figure 4; and

Figure 6 is a sectional plan taken substantially on line 6—6 of Figure 4, and showing the projections provided on either side of the top tooth.

The manganese nigger bar may be conveniently formed with a shank 1 which is of substantial I-beam section, comprising the flanges 1^a which are connected by the web 1^b. This shank terminates in a head which may conveniently be made of a prolongation of the flanges 1^a, but the web 1^b in way of the lower tooth extends upwardly and outwardly to the edge of the flanges to form a lower tooth stop as shown at 15. Any number of teeth 6 may be provided, which teeth are adapted to be positioned between and have contact with tooth stop (or spacer) forming connecting portions 15', similar to 15, as particularly shown in Figure 1. This head terminates in a shoulder 7 rounded toward the log engaging edge, disposed at the top of the bar, and of less diameter than the head flanges. The shouldered head is connected to the front face of the flanges by the sloping portion 14, so disposed that when the upper tooth, which is preferably of T construction (as shown in Figure 5), is in raised or inoperative position, (as shown in the dotted lines in Figure 4), this tooth will clear the front edge of the bar.

The shank at its lower end terminates in a base portion 2 which may be provided with a continuous flange 13 and a web 12 therebetween having the lightening hole 11 therein. Said base portion is provided with spaced

flanges 3 having fastening holes 14' and 14" having suitable bushings for the reception of fastening means between the bar and the usual operating and anchoring means respectively. Any operating means may be used, as, for instance, the usual piston and cylinder arrangement, and it is found desirable to pivot an anchor bar to one hole 14" to move the bar in a predetermined manner in 5 a guide slot and to take side strain off the cylinders and prevent backing away from the log.

The teeth are held in position between the flanges of the head by a novel pivot means 15 which comprises a hollow T-shaped pin 9 which is adapted to be inserted in the eyes provided in the flanges and which extends nearly through the opposite flange. A rivet 8 is inserted in this hollow pin. This rivet 20 will extend through the pin, and the point will be clinched on a suitable washer 16 providing a flush construction with the outside of the flange, or will be inserted the opposite way and clinched in the head of the pin. 25 The pinhead fits tightly in the recess provided in the flange and cannot move or rock thereby preventing undesirable wear on the eyes. It will be seen that the pivot formed is of very rugged construction, 30 though due to the graduated recess in the pin head, the rivet may be removed easily by the use of a cold chisel or other means applied to the rivet point. This form of the pivot has been found desirable in that there 35 is no tendency for the pivot to work loose, and it is of considerable stronger construction than the usual rivet or bolt pivot.

It is to be understood that the modification shown is merely by way of illustration and 40 not limitation as many and various forms will occur to those skilled in the art.

I claim:

1. A nigger bar comprising, in combination, an integral base and shank, the latter 45 being substantially I-shaped in cross-section, and a plurality of teeth mounted in openings within the shank, the mounting for each of said teeth comprising a hollow pin having a headed portion adapted to engage the walls 50 of a recess formed in the shank to prevent rotation of the pin, and a headed rivet extending through the hollow pin to prevent accidental displacement thereof, the heads of said pin and said rivet being disposed within 55 the body of the shank.

2. A nigger bar comprising, in combination, an integral base and shank, the latter being substantially I-shaped in cross section, and a plurality of teeth mounted in openings 60 within the shank, the mounting for each of said teeth comprising a hollow pin having a T-shaped headed portion adapted to engage the side walls of an elongated recess formed in the shank to prevent rotation of the pin, 65 and a headed rivet extending through the

hollow pin and upset at the extremity opposite to the headed portion to prevent accidental displacement of the pin, the head of said rivet being disposed within a recess formed in the shank, and one of the heads 70 of the pin and rivet being smaller than the recess within which it reposes to render it readily accessible in dismantling the mounting.

Signed at Berkeley, California, this 11th 75 day of August, 1927.

COREY C. BRAYTON.
